UNITED STATES PATENT OFFICE.

ERNEST GRÉBY, OF ISSY, FRANCE.

STARTING DEVICE.

1,205,885.

Specification of Letters Patent. Patented Nov. 21, 1916.

Application filed July 6, 1914. Serial No. 849,205.

To all whom it may concern:

Be it known that I, ERNEST GRÉBY, a citizen of the French Republic, and resident of Issy, France, have invented certain new and 5 useful Improvements in Starting Devices, of which the following is a specification.

The invention has for its object to provide a device by means of which any internal combustion motor for automobiles, flying 10 machines and the like may be started by means of an automatically working mechanical device actuated by a blade spring with dynamic compensating means having a relatively high power and suppleness.

15 The automatic starting device may be controlled by hand and automatically in an absolutely concealed and simple manner.

The plate spring may be brought under tension immediately after it has worked and 20 maintained in a fully tensioned position. Said spring is able to impart to the motor shaft a speed of four revolutions in the second.

The automobile or the like may be braked 25 progressively and automatically until the wheels are jammed, by means of a key, when the driver leaves the automobile or the like, the braked vehicle or motor being fully fixed in such a manner that nobody can operate 30 the automatic starting device when he is not in possession of the key. These keys based on the same principle may be of different shape and dimensions according to the nature of the apparatus. The brake works 35 progressively and is very supple and powerful, and also absolutely automatic, so that it may be applied in case of emergency.

The device is shown by way of example in the accompanying drawings, in which:

40 Figure 1 is a view, partly in section, of the left side part of the automatic barring engine up to line A—A. Fig. 2 is a view partly in section of the right side part of the same; Fig. 3 is a top view showing the 45 connecting means of the laminated steel blade spring forming the resilient link of the spring. Fig. 4 is a top view of the left side portion of the barring engine up to line B—B. Fig. 5 is the right side portion of 50 same.

The starting device comprises a plate spring R^3 connected with a drum R by means of a resilient organ formed of a plurality of laminated steel strips 3 , able to be 55 readily wrapped around said drum. The number of strips depends from the power of

spring R^3 ; they are superposed and united so as to form two loops, one of which is fastened to the plate spring R^3 and the other one to a pivot Y provided on the drum R . When the spring R^3 is released, the drum R is rotated 85 degrees. The position of the axis of the drum and its diameter are determined by the arc $K'—J'$ (Fig. 3) of a dynamic compensator. The spring R^3 and the dynamic compensator form the starting device.

The compensator comprises: a drum R operated by the plate spring R^3 and keyed on a shaft L ; a lever K rigidly connected with shaft L ; a slide or lever J transmitting the action of spring R^3 and the rotary motion of the drum R ; through the interposition of lever K , to a second device comprising: a toothed wheel H loosely mounted on a shaft L' at the upper end of which is loosely mounted a pulley P' . The shaft L' forms the support and center of rotation of the slide or lever J and the fulcrum of the lever arm of the power, because the pulley P' forms the center of rotation and the support of the slide or lever J when the latter transmits the power imparted by the lever K at J' , to a rail I by the intermediate of a roller L' . A toothed wheel H' engages 80 wheel H rotatable on the fixed shaft L' . The force or power exerted on the pitch circle of said wheel H' is constant, owing to the dynamic compensator. Effectively the loose pulley P' forms continuously the center of 85 rotation of the slide J and also the center of the sliding motion of same. Now said slide J , by means of its end, part J^3 and by means of a pivot integral with said part and 90 on which is hinged the free end of lever K , is connected with drum R and receives the uniformly decreasing strains of the spring R^3 . By its opposite end J^4 , provided with a pivot on which is loosely mounted the roller L' , the slide J operates the toothed 95 wheel H by pressing on the rail I which is integral with said wheel H . The length of rail I and its direction is that of a radius of wheel H . Spring R^3 is calculated so as to furnish a relatively high power when it is released, with a loss of tension of a kilogram by square inch; that the work of the slide and the point of resistance to be determined on the pitch circle of wheel H , are considered as constant at every start of the motor.

100 The end of lever K is the point where the power is applied, and when the slide J is 105 110 115

considered as a lever $K' P' I'$ and the pulley P' as the fulcrum, the power transmitted to the pitch circle of wheel H , at the starting of the motion, is in an inverted proportion to

$$\frac{I'P'}{K'P'}$$

and gives the value of the constant force 10 which should be kept up during the releasing of spring R^3 and applied on the pitch circle of H . During the working of the starting device the pulley I' runs along the rail I and comes nearer the fulcrum P' which 15 is the center of wheel H and moves same in the direction of the arrow; during the same time the end K' of lever K moves along the arc $K' J'$ which is the line formed by the ends of the lever arms increasing from K' 20 to K^n , so as to continuously balance the resistance, which latter remains constant at the various starts of the starting device, whatever may be the degree of tension of R^3 . Owing to the dynamic compensator, 25 the driving shaft of the motor is operated by spring R^3 with the same power and speed from beginning to end of the spring effort. The maximum number of revolutions imparted to the driving shaft by the starting 30 device before it should be tensioned again, is ten.

The constant power is transmitted by the wheel H to the pinion H' keyed on a shaft L^2 on which is also keyed a bevel wheel G 35 engaging a wheel G' . The shaft L^2 is rotated by the wheel H' . Wheel G' is keyed on a steel sleeve E loosely mounted on a shaft L^3 . The portion of sleeve E opposite to pinion G' is provided with clutches engaging corresponding clutches provided on a sleeve E^2 slidingly mounted on shaft L^3 . The opposite end of sleeve E' is flat; on 40 said flat end bear rollers of a disengaging fork D' . A spring R^6 secures the engaging of both sleeves E' , E^2 . On the shaft L^2 is keyed a helical wheel X operated by a non-reversible worm V , whereby said worm operates all the above described parts, and produces the releasing or tension of the 45 laminated spring R^3 . The spring R^3 cannot operate the starting device when the disengaging of the sleeve has not been done, because the reaction of R' is exerted on the pinion X which latter cannot operate the 50 worm V because the latter is not reversible. The barring device is thus in its position of rest and ready to work. The motor or driving shaft is started by means of two chain 55 wheels, one of which, F , is secured on the sleeve E on which is keyed the wheel G' , said latter parts forming a whole loosely mounted on shaft L^3 . The second chain wheel is mounted on the connecting sleeve F^6 loosely mounted on the hollow shaft of 60 the cone engaging the fly wheel of the motor. 65

The sprocket wheel F^2 is carried upon the sleeve F^5 and is keyed for rotation therewith by means of two projections F^6 secured on or integral with said wheel and engaging corresponding longitudinal grooves provided in said sleeve F^5 (Fig. 3). Thus it will be seen the clutch sleeve F^5 is capable of longitudinal movement upon the main drive shaft of the vehicle and is operated by a shifting means to be presently described, and the movement of the sprocket F^2 with the clutch sleeve is prevented because of the resistance against throwing the said sprocket and the sprocket F^4 out of alignment with each other when connected by a chain (not shown). This clutch casing on the motor shaft is controlled by means of a pedal F maintained in the position of rest (Figs. 1 and 3) by means of a strong spring R^7 acting against spring R^2 and operating a fork F' which, when at rest, is applied by means of two rollers against the circular face of the clutch part F^5 and compresses the spring R^2 . When operating the pedal F , fork F' is disengaged from the 70 face of casing F^5 , spring R^2 acts upon said face and applies same on the clutch part F^2 , thus producing the connection between the 75 motor shaft and the barring device. 80

The shaft V , to which is keyed the worm V' , is hollow and is provided with a pin or projection engaged by a groove of a shaft V^2 , the upper end C^2 of which is square. Its opposite end receives and maintains a 85 lever Q operating the blocking brake which 90 will be hereinafter described.

On shaft V^2 is keyed a disk plate D which 95 operates mechanism $D' D^2$. Shaft V^2 moves vertically within a shaft V^3 and is only maintained in position by means of the 100 springs R^4 , R^6 . On shaft V' is further mounted a bevel gear wheel T engaging a similar wheel secured to a sprocket wheel S' and loosely mounted on a shaft secured to the frame of the apparatus. The wheel S' , 105 by means of a chain, operates and is operated by means of a second wheel S keyed to a shaft N^2 . The automatic retensioning device is formed by the shaft N^2 , wheels S and S' , the bevel gear wheels T , the clutch 110 device N , N' and a pulley O . On the clutch part N is engaged one of the lever arms M , M' , the other arm of which extends laterally with respect to the wheel H into the path of a projection or stud M^2 secured on 115 said wheel H . When the latter rotates an angle of 10 degrees, the lever is disengaged, and operated by the spring of clutch part N , secures the connection between N and N' . If in this instant the pulley P of the change 120 speed gear is operated, owing to the starting of the automobile, all the above described parts will be put in motion and the worm V operates all the parts described until now 125 and the spring R^3 of the barring device 130

will be tensioned. The strain on the worm V is about $1\frac{1}{2}$ kilos. N, N' are disengaged by M.

The safety key A controlling the starting device is a removable combination key. For winding up the spring R³ by hand, the key A is introduced into the sleeve B². Said sleeve is made of bronze and is provided at the lower third part of its length with three short ribs having different shapes and sizes, and symmetrically disposed inside said sleeve B² at B. Immediately below the ribs B slides the hollow shaft V² having a square or any other geometrically shaped end C, or (except a cylindrical one). When introducing the key A, the grooves of shaft A' successively engage the corresponding ribs B after which a square recess provided at the end of the key, engages the square C of hollow shaft V³. When the key is wholly introduced, the key handle is turned by hand, whereby the worm V rotates and the spring R³ is tensioned.

The lower end of shaft V' is provided with two small annular jaws, between which is pivoted one of the arms of the cranked lever Q connected by means of three links Q⁵ and two further levers Q' and Q² to a lever Q³ keyed on a shaft Z supported on both its ends by means of small bearings mounted on the bars of the frame.

When the key A is withdrawn from sleeve B², the spring R' supporting the disk plate B, acts on the latter, which raises the hollow shaft V³ and the lever Q' in combination with the spring R³, operates the mechanism Q, Q', Q² Q³. The shaft Z is rotated 30 degrees together with an arc shaped rack Q⁴ slidable on shaft Z but prevented from rotating on same. Said rack compresses a coil spring R⁴ of square section engaged around the shaft and is resiliently applied against a toothed crown integral with the brake drum P of the change speed gear or fixed onto same. When the teeth of the rack Q⁴ register with the hollows of the toothed crown, the pitch of which is equal to that of the rack, the coupling is operated, and when the automobile is not running, the latter is so to say locked; the change speed gear can no longer work and the rear wheels are blocked. If however in case of emergency the change speed gear is operated, the coupling will be done automatically as above stated, but the rack, carried with the toothed crown of Z (Fig. 1) compresses the spring R⁴ and progressively brakes the brake drum of the change speed gear until the automobile is wholly stopped. Nobody is able to start again the automobile without making use of the key A, which should be engaged into the sleeve at the first step. The second step corresponds to the position of the key for starting.

For starting the above described auto-

matic starting device, two motions are required: first the driver operates the pedal lever F for coupling F² and F³, that is to say, for coupling the driving shaft with the barring device, then the driver presses on the top A' of the key for pushing the disk plate D downward, the latter operating the device D' D² and producing the uncoupling at E.

The various parts of the starting device being no more influenced by the worm V, the motion of said device is transmitted to the driving shaft of the motor by the intermediate of F², F³. The pedal F and key A may be maintained in the lowered position until the motor starts. But in view of the speed imparted to the driving shaft and of the centrifugal force of the fly wheel, the starting device may be stopped after half a revolution, the fly wheel alone proceeds starting the motor, provided that the motor is not yet started.

For stopping the starting device, and before releasing the pedal lever F and the key A, it is necessary, for avoiding shocks during the coupling of E and the uncoupling of F² and F³, to brake the spring R³. With this object in view, use is made of the uncoupling pedal of the automobile, which uncouples the motor and pushes the sleeve, on which is secured the coupling cone, against a part G² fixed to the change speed gear and having its face, adjacent to that of F³, coated with a disk made of fibers. The part F³, which is carried with the sleeve and the wheel F², being secured onto the sleeve of the cone, the mechanism of the starting device is progressively braked together with spring R³. At this instant the key A is released by the driver and moves upward in its position of rest and E is coupled again. Finally both pedals are released. These motions only require several seconds and little attention. For blocking the automobile, the key A is simply withdrawn. For unblocking, the key is engaged downwardly to the first step or stop of the key, provided on the fixed sleeve B.

Having now fully described my said invention, what I claim and desire to secure by Letters Patent, is:

1. A starting device for internal combustion engines including a resilient element for accumulating energy, means for placing and holding the element under strain including a clutch and worm gears, means for releasing said element, means for transmitting the expended energy of the element when released to the engine shaft, and means in said transmitting means for regulating the expenditure of energy whereby the turning effort on the engine shaft is kept constant throughout the releasing period of the resilient element.

2. A starting device for internal combus-

tion engines including a resilient element, means for placing the element under strain, holding means for retaining the element under strain, said latter means including a 5 clutch and worm gears, key operated means for releasing the holding means, means for imparting the accumulated energy of the resilient element when released to the engine shaft for rotating the same, and means for 10 increasing the application of power to the engine shaft as the energy of the resilient element is expended, said means including a rotative member and a system of oscillating levers coöperating with said member.

15 3. A starting device for motor vehicles including a resilient element, manually operated means for placing and holding the element under strain, means for releasing the resilient member, a pulley, a flexible element connecting the resilient member with the pulley whereby said pulley is rotated when the resilient member is released, a driving gear, means on the pulley for engaging the driving gear for rotating the 20 same, said means being adapted to act upon the gear with various degrees of effort so as to maintain the rotating speed of the driving gear constant throughout the releasing period of the resilient member, and 25 means connecting the driving gear with the motor shaft for rotating the same.

4. A starting device for motor vehicles including a resilient element, means for placing and holding said element under 35 strain, means for releasing said holding means, a pulley, a flexible band connecting the resilient member with the periphery of the pulley, a lever mounted for rotation with the pulley, a driving gear, a radial 40 projection on the driving gear, a link pivoted at one end to an extremity of the lever, a roller on the forward end of the link adapted to engage the projection, and means for connecting the driving gear with the 45 motor shaft.

5. A starting device for motor vehicles including a resilient member, means for placing and holding the member under strain, means for releasing the holding 50 means, a shaft, a pulley mounted on the shaft, a flexible band connecting the resilient member with the periphery of the pulley, a lever fixed to the pulley shaft, a spur gear eccentrically mounted in relation 55 to the pulley shaft, a radial projection on the driving gear, a yoke adapted to reciprocate diametrically across the face of the driving gear, said yoke being pivoted at one end to the free end of the lever, a pulley 60 mounted on the other end of the yoke for engagement with the radial projection, and means for connecting the driving gear with the motor shaft.

6. A starting device for motor vehicles 65 including a resilient member, means for

placing the resilient member under tension which comprises a worm shaft, a worm wheel meshing therewith and having a worm wheel shaft, a bevel gear on said shaft, a second bevel gear meshing therewith, a spur gear adapted to rotate with said second bevel gear, a second spur gear adapted to mesh with said first mentioned spur gear, a pulley, variable means connecting the pulley with the last mentioned gear, and a flexible member connecting the pulley with the resilient member, and means connecting the gearing with the motor shaft.

7. A starting device for motor vehicles including a resilient member, gearing between the resilient member and the motor shaft, means for placing the resilient member under strain comprising a tubular lock casing provided with wards, said casing being adapted to receive a key provided with a crank arm, a worm shaft having one end projecting into the lock casing and forming engaging means with the key, a worm wheel meshing with said worm and having a shaft and a gear on said shaft for connection with the aforesaid gearing whereby upon insertion of the key and rotating the same the resilient member may be placed under strain.

8. A starting device for motor vehicles including a resilient member, a pulley, a flexible band connecting the resilient member with the pulley, a spur gear, variable means connecting the pulley with the spur gear, a second spur gear meshing with said first gear, a bevel gear adapted to rotate with 100 said second gear, a second bevel gear adapted to mesh with said first bevel gear, a shaft for said second bevel gear, a clutch on said shaft, means for normally holding the clutch in engagement, means adapted to be manually operated for rotating said clutch shaft to place the tensional member under strain, a sprocket on said shaft, a sliding sleeve mounted upon the motor shaft, a second sprocket mounted on said sleeve, and a 110 chain connecting the two sprockets.

9. A starting device for motor vehicles including a resilient member, manually operated means for placing the member under strain, automatically operated means for replacing the member under strain comprising a pulley mounted on the motor shaft, a second pulley mounted upon a counter-shaft, a flexible band connecting the two pulleys, gearing connecting the counter-shaft with 115 the resilient member for placing the resilient member under strain when said counter-shaft is rotated, a clutch on the counter-shaft which when in released position permits said shaft to rotate freely, and means 120 on the gearing for causing the release of said clutch.

10. A starting device for motor vehicles including a resilient member for accumulating energy, means for imparting the ac- 130

5 cumulated energy to the motor shaft, key
operated means for placing the resilient
member under strain, a pulley mounted on
the motor shaft and having a gear formed
thereon, means operated by the pulley for
automatically placing the resilient member
under strain, a shaft mounted adjacent the
gear, a rack bar splined to the shaft for
engagement with the gear, a coil spring on
10 the shaft for resisting sliding movement of
the rack bar, a toothed segment which
meshes with said rack bar, a link connecting
the segment with the resilient member,
means operated by the aforesaid key for
15 rotating the shaft to cause engagement be-
tween the rack bar and the gear pulley
whereby the same is locked against rotation.

11. A starting device for motor vehicles
including a resilient member for accumulat-
20 ing energy, compensating gearing for im-
parting accumulated energy to the motor
shaft, a key controlled manually operated
shaft for placing the resilient member un-
der strain, a pulley on the motor shaft, a
25 counter-shaft, a pulley on the counter shaft,
means for connecting the two pulleys, a
sprocket wheel on the counter shaft, a jack
shaft having a sprocket, a chain connecting
the sprockets, gearing connecting the jack
30 shaft with the manually operated shaft, a
clutch on the counter shaft whereby said
shaft may be rotated freely when the clutch
is disengaged, means for normally holding

the clutch out of engagement, a gear formed
on the motor shaft, a pulley having teeth, 35
means for engaging said teeth to lock the
pulley against rotation, a system of bell
cranks and levers for operating said engag-
ing means, the primary member of said bell
crank system being operated by the manu- 40
ally operated shaft.

12. A starting device for motor vehicles
comprising in combination a sleeve slidably
mounted on the motor shaft, a co-acting
clutch member fixed to the motor shaft, 45
foot operated means for causing engagement
of the clutch members, a sprocket on the
sliding sleeve, a second sprocket, a chain con-
necting the sprockets, a resilient member for
50 accumulating energy, gearing connecting the
second sprocket with the resilient member
whereby the motor shaft is rotated when the
resilient member is expending its accumu-
lated energy, manually and automatically
55 operated means for placing the member un-
der strain, a pulley on the motor shaft for
supplying power to the automatically op-
erating means, means for locking the pulley
against rotation, said means being operated
60 by the manually operated means.

In testimony whereof I have hereunto set
my hand in presence of two witnesses.

ERNEST GRÉBY.
